DESIGN FOR A DENTAL EQUIPMENT STAND

Henry Dreyfuss, New York, N. Y., assignor to The
S. S. White Dental Manufacturing Company, a corporation of Pennsylvania

Application May 4, 1937, Serial No. 69,164

Term of patent 14 years

To all whom it may concern:

Be it known that I, Henry Dreyfuss, a citizen of the United States and a resident of New York, county of New York, State of New York, have invented a new, original, and ornamental Design for a Dental Equipment Stand, of which the following is a specification, reference being had to the accompanying drawing, forming part thereof.

The drawing represents in Figure 1 a plan view, in Figure 2 a front elevational view, and in Fig. 3 a perspective view as seen from the rear of the dental equipment stand showing my new design.

I claim:

The ornamental design for a dental equipment stand as shown.

HENRY DREYFUSS.
